UNITED STATES. PATENT OFFICE.

WILLIAM WOROBEL, OF LANSING, MICHIGAN.

SCREEN.

1,351,275.

Specification of Letters Patent. Patented Aug. 31, 1920.

Application filed December 29, 1919. Serial No. 348,153.

To all whom it may concern:

Be it known that I, WILLIAM WOROBEL, citizen of the United States, and resident of Lansing, in the county of Ingham and 5 State of Michigan, have invented certain new and useful Improvements in Screens, of which the following is a specification.

This invention relates to window screens, and more particularly to screens which may 10 be rapidly and readily lifted or lowered at will.

The main object of my invention is to provide a window roll screen which may be rolled up in the manner of a window shade, 15 and likewise lowered, thus eliminating the difficulty of having to lift out screen frames, or handle them in the manner of the lift window, as is the case with screens at present in use.

20 Another object of the invention is to provide a novel and practical locking and releasing means for said screen, so that the same may be securely and releasably held in any position in its frame.

25 The above and other objects will become apparent in the description below, in which characters of reference refer to like-named parts in the drawings.

Referring briefly to the drawings, Figure 30 1 represents a front elevational view of my device applied to a window, as viewed from the exterior of the house, taken substantially on the line 3—3 of Fig. 5.

Fig. 2 represents a side view taken substantially on the line 2—2 of Fig. 1.

Fig. 3 represents a front elevational view of my device applied to said window and viewed from the interior of the house.

Fig. 4 is a longitudinal cross-sectional view of my screen in rolled-up position, 40 showing the spring actuating mechanism.

Fig. 5 is a side elevational view taken substantially on the line 5—5 of Fig. 3.

Referring now in detail to the drawings, 45 the numeral 1 represents the window frame, and 2 the screen which is rolled upon a cylinder 3 pivotally mounted to a shaft 6 rigid to supports 4 secured to said frame. A spring 7 is coiled about said shaft and has 50 one end secured to said shaft and the other to said cylinder, as shown.

A hood or cover 5 is provided pivoted upon pins 5^a, so that the same may be raised at will to expose said rolled-up screen, the 55 cover in its lower position being provided

for the purpose of concealing said rolled-up screen and to protect the same.

The sides of said screen 2 are adapted to ride in runners 10^a in the window frame, the inner sides of said runners being provided with serrations 10. A lower border 9 is attached to said screen by grasping which the same may be pulled downward. This border is narrowed toward the upper part as at 15, the space between the latter and the former 60 being enlarged to provide on each side of the screen a hollow tube 20 having an enlarged cylindrical chamber 15^a on the inner side of said tube. A rod 11 passes through each tube 20 and through the adjacent chamber 15^a, one of said rods 11 being attached to a link 21, and the other to a bell crank 14 which has a handle portion 16. In each of the chambers 15^a a spring 12 is coiled about the rod 11, and said rod is provided with a stop in the form of a nut 12^a at its outer end, that is, of the portion within the chamber 15^a. The free ends of the rods 11 are adapted to normally engage the serrations of the runners 10^a, by force of the 75 coiled springs 12.

It is now apparent that, in order to lower the screen 7, the border or ledge 9 is grasped in the hand and simply pulled downward. In order to raise the screen, the handle 16 80 is grasped and pulled in a counter-clockwise direction, thus disengaging the rods 11 from the serrations 10, whence the force of the spring 7 causes the screen to rise.

Having thus described my invention, 90 what I claim and desire to secure by Letters Patent, is as follows:

A roll screen comprising in combination a shaft supported on a window frame, a drum rotatable about said shaft, a coiled spring 95 having one end attached to said drum and the other to said shaft, a screen adapted to be rolled upon said drum, a hood for said drum and the screen thereon, hingedly mounted upon said frame, vertical runners 100 in the sides of said frames having serrated interior surfaces, said runners adapted to guide said screen in its vertical movement, and releasable means for retaining said screen in any desired position in said frame 105 comprising horizontal tubular members at the bottom of said screen, the inner ends of said members having enlarged chambers, rods passing through said tubes and adjacent chambers, the outer ends thereof adapt- 110

ed to engage said serrated surfaces, a stop on each of said rods within said chambers and coiled springs about said rods within said chambers, a bell crank having one of 5 said rods attached thereto, a link having the other of said rods attached thereto, said link being also attached to said bell crank,

and a handle on the latter for actuating said rods.

Signed at Lansing, in the county of Ing- 10 ham and State of Mich., this 20th day of Dec., A. D. 1919.

WILLIAM WOROBEL.
